DEVICE FOR CONTROLLING THE TRANSMISSION OF POWER TO PUMPS

John C. Myers, Sperry, Okla., assignor of one-half to J. W. Scott Drilling Company, Tulsa, Okla., a corporation of Texas

Application August 25, 1941, Serial No. 408,150

6 Claims. (Cl. 103—23)

This invention relates to devices for controlling the transmission of power to pumps, and more particularly to the operation of pumps for lifting liquids, the object being to provide an efficient means for automatically stopping such pumps in response to the delivery of air, or other gaseous fluid to the pumps.

The capacity of many pumps is greater than that of more or less uncertain sources of liquid delivered to the pumps, and it is usually advisable to stop the pumps when the delivery of liquid is discontinued. For example, water or oil may be profitably pumped at intervals from many wells without exhausting the supply of liquid, but the intervals are usually uncertain, and the delivery of air or other gas to the pumps is likely to result in abrasion at the pump itself, and destructive stresses in the operating mechanism. By automatically stopping such pumps when the delivery of liquid is discontinued, the present invention positively eliminates the above mentioned hazard, and provides for safe and economical pumping of the liquid.

In the use of pumps for lifting oil from wells, a single operator is often required to attend to the pumping of many widely scattered wells. The operator usually begins by going from one well to another to start the pumps, or to inspect the pumping mechanism, and he then attends to other duties. Experience has very clearly shown that when the flow of oil to such pumps is discontinued, the pumps should be immediately stopped, but in actual practice the operator is unable to constantly observe the conditions at all of the wells, especially where the wells are widely separated and a number of pumps are operating at the same time. A similar condition arises when a person has only one well to contend with, as a single pump does not usually justify constant attention, and may be inspected only once or twice a day, perhaps to start the pump in the morning and stop it in the evening.

However, the operation of a pump after the flow of oil is discontinued results in several serious disadvantages, due to the delivery of air, or other gaseous fluid, to the pump. This condition produces a churning action which emulsifies the oil remaining in the well, and causes undue wear on the working parts of the pump, at the same time subjecting the pumping mechanism to destructive jerking which causes fatigue in the metal and is likely to break the sucker rods, thereby requiring difficult "fishing" to remove the broken rods.

The emulsified oil is a very troublesome product not acceptable to pipe line companies, and ex-

cessive friction in the working barrel of the pump requires the operators to pull the long tubing, sucker rods and pump from the deep well, in order that the worn parts may be replaced. All of this involves a loss of production of oil during the period required for repairs, as well as increased operating costs, and the production of the objectionable emulsified oil for some time after the required pumping mechanism is restored and placed in service.

Another important advantage of the invention appears in the fact that it permits the ordinary simple pumping equipment to be safely used in pumping oil from very deep wells. Heretofore, such simple equipment comprising a reciprocable plunger near the bottom of the well, and sucker rods connecting the plunger to operating means above the ground, has been regarded as unsafe for pumping oil from very deep wells wherein continuous pumping would temporarily exhaust the wells. The destructive strains and abrasion due to delivery of air or gas to the plunger are likely to break the extremely long sucker rods, or cause other injury that would be impossible, or not feasible, to repair in a very deep well. The new device automatically stops the pumping mechanism in response to the delivery of air or gas to the pump plunger, thereby providing for safe and economical pumping of oil or other liquid from deep wells.

With the foregoing and other objects in view, the invention comprises the novel construction, combination and arrangement of parts herein-after more specifically described and shown in the accompanying drawings, which illustrate one form of the invention. However, it is to be understood that the invention comprehends changes, variations and modifications within the scope of the claims hereunto appended.

Fig. 1 is a diagrammatical view of a pumping apparatus embodying features of this invention.

Fig. 2 is a vertical section on a larger scale, with parts broken away, showing the pump plunger which operates in a cylindrical working barrel near the bottom of the well.

Fig. 3 is a top view illustrating a stopping device adapted to discontinue the transmission of power to the plunger when air or other gaseous fluid is admitted to the plunger.

Fig. 4 is a side view of the device shown in Fig. 3.

Fig. 5 is a longitudinal section on the line 5—5 in Fig. 3.

Fig. 6 is a section on the line 6—6 in Fig. 4. To understand the principle of the invention,

one should bear in mind certain conditions existing in an ordinary pump. Therefore, without in any way limiting the claims, I will briefly describe a few details of an oil well pump, and then refer to special conditions employed by me to control the automatic stopping device.

An ordinary simple pump of this kind, shown in Fig. 1 and Fig. 2, comprises a cylindrical working barrel 10 located near the bottom of the well, and a string of tubing 11 through which the oil is lifted from said working barrel to a discharge pipe 12 above the surface of the ground. A pump plunger 13 reciprocating in the working barrel 10 is usually operated by a string of sucker rods 14 extending upwardly from the plunger and connected to the operating mechanism above the ground. The bottom of the working barrel 10 may be equipped with a simple check valve 15 to provide for the admission of oil to the working barrel. The reciprocating plunger 13 may be equipped with a traveling check valve 16 which opens during each downward stroke, as the plunger falls in the working barrel, and closes in response to each upward stroke when the plunger is lifted to discharge the oil. These movements of the plunger and check valves draw the oil from the surrounding casing 17 into the working barrel 10 and thereafter lift the oil through the tubing 11 which extends upwardly from the working barrel.

Attention is now directed to the following conditions:

The weight to be lifted consists of the long string of sucker rods 14, and the plunger 13, and the weight of the long column of liquid extending from the check valve 16 in the plunger to the discharge pipe 12 above the ground. However, during each normal downward stroke, the check valve 15 at the bottom of the working barrel is closed, and there is a column of oil extending from this bottom check valve to the upper end of the tubing 11. As a consequence, during each normal downward stroke, the sucker rods and plunger merely fall in this column of liquid, and the weight is then limited to the actual weight of the sucker rods and plunger, minus the buoyant effect of the body of liquid, so that the falling weight during the normal downward stroke is even less than the actual weight of the sucker rods and plunger.

When air or gas is drawn into the bottom of the working barrel 10, the weight to be lifted during an upward stroke would again consist of the sucker rods and plunger, plus the weight of the tall column of oil supported on the plunger. However, if we assume that air or gas is drawn into the working barrel, and that there is no oil between the check valve 16 in the plunger and the check valve 15 at the bottom of the working barrel, the weight during a downward stroke would be approximately the same as the weight to be lifted during an upward stroke. In this event the check valve 16 in the plunger will remain closed, due to the downward pressure of the tall column of oil. Instead of merely falling in a buoyant liquid, the plunger is now forced downwardly by this very heavy column of liquid, and the air below the plunger will be readily compressed by this high pressure, or forced backwardly through any leak at the bottom check valve 15.

I will hereinafter explain how I take advantage of this abnormal weight during a downward stroke to actuate the automatic stopping device,

thereby stopping the transmission of power to the pump.

The operating means shown in Fig. 1 comprises a pump jack 18 having a pivotal support 19 and connected by means of a cable 20 to a "polish rod" 21 at the upper end of the string of sucker rods 14. The means for operating said pump jack comprises a pull line 22 connected to the jack, and an eccentric 23 driven by a rotary power shaft 24, said eccentric being surrounded by a band 25 connected to a pull rod 26.

To illustrate a suitable means for transmitting power from the pull rod 26, I have shown a hook 27 at one end of said pull rod, and a link 28 pivoted at 29. The hook is normally coupled to the link 28 as shown by full lines in Fig. 1 and Fig. 4, but under certain conditions, the hook will move to the left independently of the link, thereby permitting said link to drop by gravity to the position shown by dotted lines. In other words, the link 28 is an uncoupling member adapted to release the pump plunger from the source of power.

The means for connecting the link 28 to the pull line 22 may include a driving tube 30 extending from said link and a driven tube 31 connected to said pull line 22 as shown in Figures 1, 3 and 4. The tubes 30 and 31 are aligned with each other and slidably supported in a stationary guide tube 32 fixed to a stationary post 33. The inner ends of the slidable tubes 30 and 31 are separated from each other, but in the specific form of the invention herein shown, these tubes 30 and 31 are connected together by means of a wire cable 34 made of spring steel and having its ends firmly connected to the outer ends of said slidable tubes, as shown in Fig. 5, wherein 35 indicates lead joints permanently connecting said cable to the outer ends of the tubes 30 and 31.

Therefore, the lifting power is transmitted from the hook 27 through the cable 34, said cable being tensioned during the lifting strokes when the column of liquid is moved upwardly on the pump plunger, and permitted to relax when the plunger moves downwardly in the column of liquid. The slidable tubes 30 and 31 reciprocate with the cable 34, and one of these tubes can be conveniently employed to stop the transmission of power to the pump plunger. For example, the stopping device may include an abutment, or stop member, 36 in the form of a weight normally located above the path of the reciprocating tube 30, as shown in Fig. 5. A latch 37 normally retains the stop member 36 in the inoperative position shown in Fig. 5, but when this latch is released, said stop member will fall into the path of the tube 30, and the inner end of said tube will eventually engage said stop member 36 during a downward stroke of the pump plunger. When this occurs, the power hook 27 will move to the left independently of the tube 30, so as to release the link 28 at the outer end of said tube 30. The link 28 then drops to the position shown by dotted lines in Fig. 4 to discontinue the transmission of power to the pump plunger, while the stop member 36 cooperates with the inner end of tube 30 to limit the downward movement of the pump plunger. Thereafter, when the operator desires to again proceed with the pumping operations, the link 28 is lifted into the path of the reciprocating power hook 27, and after the tube 30 is released from the stop member 36, the latter can be readily lifted and engaged with the latch 37, as shown in Fig. 5.

The means for releasing the latch 37 to automatically discontinue the transmission of power may include an operating rod 38 extending from said latch and having a free end portion 39 movable vertically in a vertical guide 40. A trigger 41 is secured to the operating rod 38 by means of a set screw 42, which permits the trigger to be secured in different positions on the rod 38. Said trigger 41 is to be actuated by an automatic stopping member 43 carried by the tube 31 and projecting through a wide longitudinal slot 44 in the stationary tube 32. This automatic stopping member 43 is movable longitudinally and transversely in the long wide slot 44, and it reciprocates with the tube 31 during the pumping operations.

Before describing the peculiar movements of the automatic stopping member 43, I will state that it may be provided with an abrupt abutment surface 45 at one end, and an inclined cam surface 46 at the opposite end. Under certain conditions to be hereafter described, the abrupt abutment surface 45 strikes an abrupt abutment surface 46' on the trigger 41 while the tube 31 is moving to the left, thereby moving the rod 38 to the left and releasing the latch 37 from the stop member 36, so as to automatically stop the pump plunger. Under other conditions, the inclined surface 46 of the member 43 moves to the right under an inclined surface 47 of the trigger 41, but this merely imparts an idle upward movement to the free end of rod 38 and does not tend to release the latch 37.

The foregoing details provide a suitable series of stopping members 36, 41 and 43 which I have found satisfactory in actual commercial practice, but any other suitable stopping device may be employed in connection with the separate and distinct features of my oscillatory control device which includes an oscillator driven by the source of power, and a stopping member controlled by said oscillator.

Without limiting the invention to specific details of the oscillatory control member, I will state that it preferably oscillates in response to variations in the load at the pump plunger, so as to automatically discontinue the transmission of power to the plunger when a gaseous fluid is delivered to said plunger. If desired, the oscillation can be conveniently obtained through the medium of a torsional member made of spring material and free to twist and untwist in response to variations in the load at the pump plunger.

To illustrate a suitable oscillatory control member I have shown the helical cable 34 having its ends connected to the slideable tubes 39 and 31. In assembling the device, a forcible untwisting movement is imparted to this cable by holding the tube 31 and turning the tube 39. For example, when the tube 31 is in the stationary tube 32, the projecting member 43 in the slot 44 will then limit the rotary movement of said tube 31 while the tube 39 is forcibly turned to impart an untwisting movement to the helical cable 34. This movement will locate the projecting member 43 at the bottom of the wide slot 44, and in actual practice I have found that an initial untwisting movement of one-half to one revolution will provide a satisfactory torsion in a cable.

To understand the effect of this specific form of the invention, one must bear in mind that the initial untwisting operation forces the pro-

jecting member 43 onto the bottom longitudinal wall of the slot 44, and that this projecting member will remain in contact with said bottom wall when the cable is relatively free of longitudinal tension. However, when the cable is subjected to a longitudinal pulling action, the resultant tension will tend to retwist said cable, thereby imparting an upward movement to the member 43 projecting from the tube 31. If the tension is great enough, this member 43 will move to the top of the slot 44.

During the normal pumping operations, the cable 34 is tensioned in response to each lifting stroke of the pump plunger, and relaxed during each downward stroke when the plunger merely falls in the tall column of liquid. The cable is free to twist and untwist in response to such variations in the load at the pump plunger, and the tube 31 oscillates with the cable.

During each normal downward stroke of the pump plunger, the cable 34 is relatively free of tension, so the projecting member 43 travels along the bottom wall of the slot 44, in a plane entirely beyond the trigger 41, so the normal downward strokes do not have any effect upon said trigger 41. During each upward stroke of the pump plunger, the cable 34 is tensioned and moved longitudinally to lift the tall column of liquid supported on the pump plunger. This tensioning of the cable shifts the projecting member 43 to the top wall of the slot 44 where it is aligned with the lower portion of the trigger 41. However, at this time the projecting member 43 is moving to the right and its inclined face 46 may freely engage the inclined face 47 to impart an idle lifting movement to the trigger 41. This idle movement to the right does not tend to release the latch 37 shown in Fig. 5.

It will now be understood that the normal pumping strokes cause the cable to oscillate about its longitudinal axis, and that the oscillatory movements are transmitted from said cable to the sliding tube 31 and its projecting abutment member 43 without stopping the normal transmission of power to the pump plunger.

Assuming now that the delivery of liquid to the pump plunger 13 is discontinued, and that air or gas is drawn into the lower portion of the pump cylinder 10 at the check valve 15 (Fig. 2).

During an upward stroke, the cable 34 will then be tensioned as usual, due to the weight of the plunger 13 and sucker rods 14, plus the weight of the tall column of liquid supported on the plunger. However, an abnormal condition will appear during the next downward stroke. There is a body of gas below the plunger and a very heavy column of liquid above the plunger, exerting downward pressure on the check valve 16 in the plunger. Under these abnormal conditions, the weight during a downward stroke may be approximately the same as the weight to be lifted during an upward stroke. Therefore, instead of relaxing, the cable 34 will be retained under tension during the abnormal downward stroke. As a consequence, the projecting abutment 43 will be retained at the upper portion of the slot 44 where its abutment surface 45 is aligned with a portion of the trigger 41. This condition will exist at the beginning of the abnormal downward stroke of the pump plunger, and as the plunger continues its downward movement, the projecting abutment 43 will strike the stopping trigger 41, thereby releasing the latch 37 (Fig. 5) and permitting the stopping abut-

ment 36 to fall into the path of the tube 30. When the inner end of said tube 30 is stopped by the abutment 36, the power hook 27 will continue its movement to the left, so as to release the pivoted coupling link 28, thereby disconnecting the power from the pump plunger.

In this form of the invention, wherein the power mechanism is uncoupled when gas is delivered to the pump plunger, it may appear that the uncoupling operation would permit free rotation of the tube 30 which was deliberately set to produce the predetermined initial torsion in the cable. However, before this uncoupling operation is performed, the inner end of said tube 30 firmly contacts with the stopping abutment 36, and the pressure or friction at the contacting areas is very great, due to the heavy load supported on the pump plunger which tensions the cable 34 and forces the tube 30 into frictional engagement with the stopping abutment 36. This friction prevents rotary displacement of the tube 30, and said tube is not released until the pump is again started by coupling the power hook 27 to the link 28. The stopping abutment 36 is then lifted by hand and secured by the latch 37, which resets the parts for continued operation until the automatic stopping abutment 43 again actuates the stopping trigger 41.

Actual tests of the invention on a commercial scale at various oil wells have clearly shown that a simple oscillatory controlling device of the type herein disclosed provides a complete and entirely feasible solution of the old problems in this art. It has the advantages of extreme simplicity, low manufacturing costs, unexpected durability, and the outstanding advantage of absolute certainty in its effect upon the stopping device.

Instead of adding a source of danger to persons employed in operating the pumping mechanism, the simple device herein shown lacks a number of the usual elements of danger, and almost entirely eliminates the risk of personal injury at the means for connecting and disconnecting the power mechanism.

I claim:

1. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder when the flow of liquid is interrupted, and a source of power to operate the plunger, the improvement which comprises a stopping device to discontinue the transmission of power to the plunger when a gaseous fluid is admitted through said inlet, said stopping device including a torsional oscillator through which motion is transmitted from said source of power to said pump plunger, said torsional oscillator being movable longitudinally under tension during the lifting strokes of said pump plunger, and relatively free of tension during the normal downward strokes, said oscillator being free to twist and untwist in response to variations in the tension, so as to oscillate during the normal pumping operations, an oscillatory operating member driven by said oscillator, and a stopping member to actuate said stopping device, said stopping member being in the path of said oscillatory operating member when said torsional oscillator is tensioned during a downward stroke of the pump plunger.

2. In an apparatus for lifting liquid from a

well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder when the flow of liquid is interrupted, and a source of power to operate the plunger, the improvement which comprises a stopping device to discontinue the transmission of power to the plunger when a gaseous fluid is admitted through said inlet, said stopping device including a torsional oscillator in the form of a wire cable through which motion is transmitted from said source of power to said pump plunger, said wire cable being movable longitudinally under tension during the lifting strokes of said pump plunger, and relatively free of tension during the normal downward strokes, said wire cable being free to twist and untwist in response to variations in the tension, so as to oscillate during the normal pumping operations, an oscillatory operating member driven by said wire cable, and a stopping member to actuate said stopping device, said stopping member being in the path of said oscillatory operating member when said wire cable is tensioned during a downward stroke of the pump plunger.

3. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder when the flow of liquid is interrupted, and a source of power to operate said plunger, the improvement which comprises a stopping device to discontinue the transmission of power to the plunger when a gaseous fluid is admitted through said inlet, said stopping device including a torsional oscillator through which power is transmitted from said source of power to said pump plunger, a stopping member controlled by said torsional oscillator to disconnect said oscillator from the source of power, and means for retaining said torsional oscillator under a torsional stress when it is disconnected from the source of power.

4. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder when the flow of liquid is interrupted, and a source of power to operate the plunger, the improvement which comprises a stopping device to discontinue the transmission of power to the plunger when a gaseous fluid is admitted through said inlet, said stopping device comprising a pair of slidable members aligned with each other, a torsional oscillator connecting said slidable members to transmit movement from the source of power to said pump plunger, said torsional oscillator being movable longitudinally under tension during the lifting strokes of said pump plunger and relatively free of tension during the normal downward strokes of said plunger, said torsional oscillator being free to twist and untwist in response to variations in the tension, so as to oscillate one of said slidable members during the normal pumping operations, and a stopping member controlled by the last mentioned slidable member.

5. In an apparatus for lifting liquid from a

well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder when the flow of liquid is interrupted, and a source of power to operate the plunger, the improvement which comprises a stopping device to discontinue the transmission of power to the plunger when a gaseous fluid is admitted through said inlet, said stopping device comprising a driving member connected to the source of power, a driven member connected to said pump plunger, a torsional oscillator connecting said driving and driven members, a guide in which the connected members are slidably mounted, a stop member movable into the path of said driving member to limit the movement thereof, an uncoupling device to disconnect said driving member from the source of power when said driving member engages said stop member, a latch to retain said stop member in an inoperative position, a trigger to release said latch, and a trip member carried by said driven member, said trigger being adjacent to the path of said trip member, said torsional oscillator being movable longitudinally under tension during the lifting strokes of said pump plunger, and relatively free of tension during the normal downward strokes of said plunger, said torsional oscillator being free to twist and untwist in response to variations in the tension, so as to oscillate said driven member and trip member during the normal pumping operations, and said trigger being in the path of said trip member when said torsional oscillator is tensioned during a downward stroke of the pump plunger, so as to release said latch and locate the stop member in the path of said driving member.

6. In an apparatus for lifting liquid from a well provided with a pump plunger to lift the liquid, a cylinder in which the plunger reciprocates, said cylinder having an inlet through which liquid

is delivered to the plunger under normal pumping conditions, said inlet providing for the admission of gaseous fluid to the cylinder when the flow of liquid is interrupted, and a source of power to operate the plunger, the improvement which comprises a stopping device to discontinue the transmission of power to the plunger when a gaseous fluid is admitted through said inlet, said stopping device comprising a driving tube connected to the source of power, a driven tube connected to said pump plunger, a torsional oscillator in the form of a wire cable connecting said tubes, a guide in which the connected tubes are slidably mounted, a stop member movable into the path of said driving tube to limit the movement thereof, an uncoupling device to disconnect said driving tube from the source of power when said driving tube engages said stop member, a latch to retain said stop member in an inoperative position, an operating member extending from said latch, a trigger secured to said operating member and adjustable to selected positions along said operating member, said guide having a longitudinal slot, a trip member carried by said driven tube and extending through said slot, said trigger being adjacent to the path of said trip member, said torsional oscillator being movable longitudinally under tension during the lifting strokes of said pump plunger, and relatively free of tension during the normal downward strokes of said plunger, said torsional oscillator being free to twist and untwist in response to variations in the tension, so as to oscillate said driven tube and trip member during the normal pumping operations, said trigger being in the path of said trip member when said torsional oscillator is tensioned during a downward stroke of the pump plunger, so as to release said latch and locate the stop member in the path of said driving tube, said stop member and driving tube having co-operating friction surfaces to prevent rotary displacement of the driving tube when it is disconnected from the source of power.

JOHN C. MYERS.
